(57) **CLAIM**

The ornamental design for a timber blade end cog adaptor, as shown and described.

DESCRIPTION

FIG. 1 is a perspective view of timber blade end cog adaptor in accordance with my new design;

FIG. 2 is a top plan view thereof; and,

FIG. 3 is a front elevational view thereof, a rear elevational view thereof being identical.

The bottom view of the timber blade end cog adaptor is not shown in the drawings or described in the specification and, therefore, forms no part of the claimed design.
